CURRENT TAP

George B. Benander, Oaklawn, R. I., assignor to General Electric Company, a corporation of New York

Application April 25, 1956, Serial No. 580,568

2 Claims. (Cl. 339—59)

The present invention relates to current taps such as cord connectors, convenience outlets and cube taps having male prongs for insertion in a convenience outlet. The principal feature of this invention is the novel design of the contacts of thin strip material of uniform width. This not only results in a minimum cost of manufacture but also provides a flat compact design which improves the appearance and is also more resistant to damage if the device is dropped or stepped upon.

In the past there have been many different constructions of the contacts of current taps. The particular design of this invention enables the use of a contact of thin strip material of uniform width for use in a current tap that is adapted to receive a plurality of attachment plugs. Since the contact strip is of uniform width, there is little or no scrap loss. Also, it is a simple matter to stamp slots in the contact strips and bend the strips along a transverse axis in the area including the slots for doubling-back the material so that the prong of an attachment plug may be inserted into the slots in one or both sides of the arms of the doubled-back portion for making electrical connection therewith.

Accordingly, the principal object of this invention is to provide a current tap with a novel contact of thin strip material of uniform width which has a series of longitudinally-spaced slots for receiving the prongs of a plurality of attachment plugs.

A further object of this invention is to provide a current tap with a pair of similar contacts of thin strip material slotted and doubled-back to make a strong electrical connection with the prongs of attachment plugs that are inserted therein.

A further object of this invention is to provide a current tap having a body of resilient insulating material with a pair of similar contacts of thin strip material molded therein and a series of longitudinally-spaced slots in the contact strip to give a double wiping action with the prongs of an attachment plug so that the prongs will clean the contact surfaces of any insulating compound in the slotted openings.

My invention will be better understood from the following description taken in connection with the accompanying drawing and its scope will be pointed out in the appended claims.

Figure 1 is an elevational view of a triple cord connector embodying my invention.

Figure 2 is a right side elevational view of the cord connector of Figure 1.

Figure 3 is a back elevational view of the cord connector of Figure 1.

Figure 4 is a view showing the position of the contacts of the cord connector of Figure 3, while the outline of the connector body is shown in dotted lines.

Figure 5 is a side elevational view taken on the line 5—5 of Figure 1 showing prongs of attachment plugs inserted in the contacts with the outline of the connector body shown in dotted lines.

2

Figure 6 is an isometric view of the contacts of Figure 4.

Figure 7 is a plan view showing the blank of the contact strip before it is bent into its final shape.

5 Figure 8 is a cross-sectional elevational view similar to that of Figure 5 taken on the line 8—8 of Figure 3.

Referring in detail to the drawing, and in particular to the preferred embodiment of Figures 1 and 2, 10 represents a triple cord connector that is molded of a suitable resilient electrical insulating compound onto the end of a two-conductor cord 11. A triple cord connector is designed to receive the prongs of three attachment plugs at one time. In the present design there are attachment plug-receiving openings 12 in one side face of the connector and a similar pair of openings 13 slightly offset therefrom in the back face of the connector. A third set of openings 14 are formed in the end of the connector to complete the assembly. The rectangularly shaped depression 15 seen above the openings 12 in Figure 1 serves a dual function as a finger grip useful in separating the connector 10 from an attachment plug inserted in the opening 14 in the end of the connector, and also of reducing the amount of molding compound and hence the cost of manufacturing the subject connector.

25 Attention is now directed to Figure 7 of the drawing showing the blank of one of the contact strips 16 of thin strip brass of uniform width which is a very important consideration of this invention. The terminal end 17 of the contact strip has a series of longitudinally extending knurlings 18 which establish a tight grip on the bare strands 19 of the cord 11, as seen in Figure 6. The conductor 19 is first placed transversely across the knurlings 18 and then the terminal end 17 is folded over the conductor and crimped thereto to form a good electrical connection. Three slotted openings 20 are stamped in the contact strip 16 which are adapted to receive the prongs of an attachment plug as will be better understood hereinafter. Each slotted opening 20 has a diamond-shaped portion 21 across which a transverse bend is made so that the contact strip is doubled-back at that point. This diamond-shaped portion serves as a tapered entrance for the prong of an attachment plug into the remaining portion 22 of the slot. It should be noticed that the remaining portion 22 is also tapered, with a narrow section 23 being adjacent the diamond-shaped portion 21 so that it is necessary for the prong of an attachment plug to pry the slot open. This, of course, results in a strong clamping action against the attachment prong.

50 The two lower slotted openings 20 of Figure 7 have only one tapered portion 22, while the uppermost opening 20 has a pair of tapered portions 22, one on each side of the diamond-shaped opening 21. A U-shaped bend is made across the diamond-shaped opening 21 of the two lowermost openings 20 of Figure 7 to form the reversed S-shaped configuration indicated as numeral 26 of Figure 6. The uppermost opening 20 also has a U-shaped bend across its diamond-shaped opening 21, but it is to extend toward the opening 14 in the end of the connector so that an additional bend 27 of Figure 6 is formed across the tapered opening 22 of the middle slot 20, as will be understood from the drawing. Finally, the free end 28 of the contact strip 16 extends laterally to the side to form an anchoring portion in the molded connector body, as is best seen in Figure 8 of the drawing.

65 The cross-sectional view of Figure 8 shows the openings 12, 13 and 14 in the connector body 10 with portions of the contact strip located therein to simplify the understanding of my invention. The contact strip may be considered as being divided into three portions; namely, the terminal end 17, the S-shaped portion 26 and the U-shaped portion 29. The lower arm 30 of the portion 26 is located in one of the openings 13 while the

upper arm 31 of the portion 26 is located in one of the openings 12. Finally, the U-shaped portion 29 is centered in one of the openings 14 in the end of the connector. Thus, as seen in Figures 5 and 8, the prongs 32 of an attachment plug may be inserted in the openings 13 for engagement in the diamond-shaped opening 21 and tapered opening 22 of the arm 30, or in engagement with similar parts in the arm 31 of the opening 12. The U-shaped portion 29 in the opening 14 is different from the others in that the prong 32 of an attachment plug is inserted in the slots in both arms of the U-shaped portion, as best seen in Figure 5.

Having described above my invention as it is applied to a cord connector for receiving as many as three attachment plugs simultaneously by using a contact strip of thin material of uniform width, it will be readily appreciated that the contact strip may be formed into shapes other than the combined S-shape and the U-shape specifically described. As an example, a cube tap with male prongs might have contact strips with three U-shaped portions formed in the manner of a cross. Alternately, the contact strip could be made for a triple tap for receiving a pair of attachment plugs on one side and a third attachment plug on the opposite side rather than in the manner shown in the drawing where there is a place for an attachment plug on the opposite sides and one to be attached in the end of the connector.

Those skilled in this art will immediately appreciate that I have formed contact strips where there is no waste of contact material since the edges do not have to be trimmed, for all of the bends in the contact strip are formed transversely thereof, which is an important feature of this invention. Likewise, I have incorporated this novel contact strip into a connector body of minimum over-all size which cannot be easily broken when dropped or stepped upon, which is a common occurrence in the home.

Modifications of this invention will occur to those skilled in this art and it is to be understood, therefore, that this invention is not limited to the particular embodiments disclosed but that it is intended to cover all modifications which are within the true spirit and scope of this invention.

What I claim as new and desire to secure by Letters Patent of the United States is:

1. A triple tap comprising a molded body of resilient

insulating material comprising three pairs of parallel attachment plug-receiving openings, an identical pair of parallel contacts of strip material arranged edgewise to each other within the body, each contact being formed transversely into an S-shaped portion having an upper arm and lower arm, the upper arm merging into a longitudinally extending U-shaped portion, the lower arm of the S-shaped portion having a longitudinal extension serving as the terminal end for connection with an electrical conductor, each bend in the S-shaped portion as well as the upper and lower arms being slotted longitudinally for receiving in each arm the blade of an attachment plug that enters from opposite sides of the body through attachment plug-receiving openings, while the entire U-shaped portion is slotted longitudinally for receiving the blade of an attachment plug that extends through an opening in the end of the body.

2. A triple tap comprising a body of insulating material having three pairs of plug prong-receiving openings, one pair of openings being at one end of the body and the other two pairs being on opposing sides of the body where they are offset from each other, and a pair of narrow electrical contact strips encased in the body in edge-wise, side-by-side relationship, each contact strip being formed transversely into an S-shaped portion and a longitudinally extending U-shaped portion merging with one end of the S-shaped portion, the opposite end of the S-shaped portion having an extension serving as the terminal end for connection with an electrical conductor, the S-shaped portion of each contact having two arms and a central section that are all parallel to each other, the two arms and the bends in each S-shaped portion being longitudinally slotted and located within the said offset plug prong-receiving openings, the central section being embedded in the body material, the U-shaped portions of the contact strips being located within the end plug prong-receiving openings.
